REMOTE CONTROL UNIT FOR AN AUTOMATIC PHONOGRAPH

Carl W. Sundberg, Bloomfield Hills, Mich., assignor to
The Seeburg Corporation, Chicago, Ill., a corporation
of Pennsylvania

Filed May 23, 1960, Ser. No. 60,686

Term of patent 14 years

(Cl. D26—13)

Fig. 1 is a front perspective view of a remote control unit for an automatic phonograph showing my new design;

Fig. 2 is a left side elevational view thereof; the right side elevational view being substantially a mirror image thereof, but with the coin-return slot omitted therefrom;

Fig. 3 is a front elevational view thereof; and

Fig. 4 is a top plan view thereof.

I claim:

The ornamental design for a remote control unit for an automatic phonograph, as shown and described.
